UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 25,451, dated April 28, 1896.

Application filed April 6, 1896. Serial No. 583,814. Term of patent 3½ years.

To all whom it may concern:

Be it known that I, FREDRIC M. PARKER, a citizen of the United States, residing at Worcester, in the county of Worcester and State of Massachusetts, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet weaving a clear understanding of the same that is sufficient to enable such person to use my invention.

The said drawing is a face view of a carpet embodying my new design.

The drawing illustrates a body and a border.

The body A consists of a substantially uniform groundwork upon which appear figures of the style known as "Indian." These figures are all alike and are placed in horizontal rows and also diagonally as to those in the next succeeding row. Each figure consists of a central ornamental figure of irregular shape resting on a star-shaped figure, from the base of which, on each side, projects an irregular conventionalized stem and leaf. From each side of the central figure projects diagonally upward and outward a conventionalized leaf shape of irregular outline ornamented with small flower-shaped figures. Above these ap-

pears an ornamental top, consisting of small figures connected by diagonal stems, forming 35 a general triangular shape.

The border B consists of a groundwork like that of the body, upon which appear figures conforming in shape and general arrangement to those of the body. The inner margin is defined by a narrow ornamental band conforming in character to the rest of the figures. The outer margin is characterized by a series of ornamental arches. Upon these rests a band with an irregular outer edge of a zigzag 45 character and ornamented with set figures between the arches. The extreme outer edge of the border is characterized by a series of set figures, each corresponding to parts of the figure appearing in the body. 50

The colors employed for the different portions of this design may be varied to suit the convenience or taste of the manufacturer.

What I claim, and desire to secure by Letters Patent, is— 55

1. In a design for carpeting, the body A, substantially as shown.
2. In a design for carpeting, the border B, substantially as shown.
3. The design for carpets, consisting of the 60 body A and the border B, substantially as shown.

FREDRIC M. PARKER.
